UNITED STATES PATENT OFFICE.

ALWIN H. BECK, OF ROCHESTER, NEW YORK, ASSIGNOR TO HICKOK MANUFACTURING COMPANY, INC., OF ROCHESTER, NEW YORK.

BELT BUCKLE.

Application filed April 25, 1925. Serial No. 25,912.

The present invention relates to belt buckles and an object of the invention is to provide an elastic belt buckle which will be strong and durable in use, and compact in form. A further object of the invention is to provide an open frame belt buckle having springs arranged on opposite sides thereof substantially throughout the length of the frame combined with an anchoring member 10 for the belt slidable on the frame between the ends thereof and acting against said springs. Another object of the invention is to provide a belt buckle of the tongue type with springs arranged on opposite sides of 15 the buckle substantially coextensive in length therewith and a belt anchoring member guided on the frame between the ends of such frame in such a manner to obtain the maximum action of the springs. 20 To these and other ends, the invention consists of certain parts and combinations of parts, all of which will be hereinafter described: the novel features being pointed out in the appended claims.

25 In the drawings:

Fig. 1 is a face view of a buckle constructed in accordance with this invention;

Fig. 2 is a rear view;

Fig. 3 is an enlarged section on the line 30 3—3, Fig. 2;

Fig. 4 is a fragmentary detail view showing the sliding connection between the belt anchoring member and the buckle body or frame;

Fig. 5 is a section on the line 5—5, Fig. 1;

Fig. 6 is a detail view of the belt anchoring member or slide;

Fig. 7 is a rear view of another embodiment of the invention; and

Fig. 8 is a perspective view of the slide employed in the last mentioned embodiment.

The belt buckle, in this instance, comprises a frame 1 with four sides having its opening bridged by a cross piece 2 which serves 45 as a pivot or fulcrum bar for the belt securing means comprising, in this instance, a tongue 3 pivoted to the bar 2.

Arranged on two opposite sides of the frame 1 are two guides, in this instance in the form of tubes or casings 4 constructed by rolling the opposite edges of the metal of which the frame 1 is formed, the tubes being situated on the rear face of the frame and having their opposed sides slotted. In 55 these tubes, helical springs 5 are arranged,

each abutting at one end of the tube, and, at the other end, an abutment 6 formed on a belt anchoring slide 7.

This belt anchoring slide comprises, in this instance, a bar which has lateral extensions 8 at opposite ends, the ends of these extensions carrying the abutments 6. These extensions 8 act as guides and cooperate with the walls 9 of the slots in the tubes so that elongated bearings are provided between the anchoring bar or slide 7 and the buckle body or frame. The slide bar 7 has at opposite ends ribs 10 for cooperating with the outer faces of the tubes or casings to prevent any wobbling of the slide anchoring 60 bar. It will be noted that the extensions project when the buckle is not expanded to the opposite sides of the fulcrum bar 2 of the tongue 3 and in this way the abutments 6 are thrown to the extreme ends of the tubes 65 4 so that the springs 5 of maximum length may be obtained.

In the use of this buckle, the anchored end of the strap is in the form of a loop 11 passed around the anchoring bar 7 and having opposed portions secured by snap fasteners 12 in a known manner. The free end 13 of the belt is passed in rear of the frame 1 of the buckle and in front of the tongue fulcrum bar 2, as well as in front of the anchored end of the belt. The tongue 3 is passed through openings 14 in the end 13. 70

The tubes or casings project rearwardly from the rear face of the front piece 1 and act as guides for the belt. The central portion of the cross bar or anchoring member is spaced from the rear face of the front piece 1, so that the adjustable end of the belt may be readily passed between the front piece and the cross bar. 75

In the embodiment of the invention shown in Figs. 7 and 8 the parts of the buckle are substantially the same. The loop 11^a in addition to being passed about the anchoring bar 7^a has its front portion lying in front of the end 1^b of the frame 1^a, this end of the frame being deflected rearwardly at 1^c so that its plane is in rear of the plane of the other end of the frame on that end with which the tongue 3^a engages. The rear member of the loop 11^a lies on the rear side of the frame end 1^b so that said frame end 1^b lies between the two portions of the loop 11^a. In this way, the frame end 1^b acts as 80 a guide for the belt end. Of course, with 105 110

this arrangement only one end of the frame will be visible at the front of the belt.

In both embodiments guides are provided at the top and the bottom of the frame between the ends of the frame and the slide moves on these guides between the end pieces. The guide is in the form of walls for slots in tubes and are engaged by the belt anchoring slide.

10 What I claim as my invention and desire to secure by Letters Patent is:

1. A buckle comprising a frame having spring casings extending along opposite sides thereof and formed with longitudinally extending slots, coil springs arranged in said casings, and a belt anchoring member extending between said spring casings having portions extending through the slots and also having enlarged portions within the 20 casings, engaging the ends of the springs and greater in thickness than the width of the slots so as to secure the belt anchoring member to the frame and means for securing the other end of the belt to the buckle 25 frame.

2. A buckle comprising a frame having spring casings extending along opposite sides thereof and formed with longitudinally extending slots, coil spring arranged 30 in said casings, and a belt anchoring member extending between said spring casings, having portions engaging the ends of the springs and elongated portions extending longitudinally of the springs and along one 35 side of each spring, said last mentioned elongated portions being guided by the walls of the slots and means for securing the other end of the belt to the buckle frame.

3. A buckle comprising a frame having 40 spring casings extending along opposite sides thereof and formed with longitudinally extending slots, coil spring arranged in said casings, and a belt anchoring member extending between the casings through said 45 slots, and having portions engaging the ends of the springs and portions for cooperating with the outer faces of the casings to prevent wabbling of the belt anchoring member and means for securing the other end 50 of the belt to the buckle frame.

4. The combination of a buckle frame formed from a single piece of sheet metal rolled at opposite edges to provide spring casings, the edges of the metal being spaced 55 from the main body to provide slots in the opposed faces of the spring casings, with springs in the rolled portions, and a belt anchoring member extending between the spring casings and having portions operating 60 in the casings through the slots against the tension of the springs and means for securing the other end of the belt to the buckle frame.

5. A belt buckle comprising a front portion, two tubes arranged on opposite sides

of the front portion, and provided with longitudinally extending slots means for adjustably securing one end of a belt to the front portion, springs mounted in said tubes, and a cross bar lying behind the front portion having its ends guided by the walls of the slots and connected with the springs in the tubes, and said bar being spaced between its ends from the plane of the rear face of the front portion, so that a belt end secured by the adjustable securing means may lie between the cross bar and the front portion. 75

6. A belt buckle comprising a front portion, two tubes arranged on opposite sides of the front portion, and provided with longitudinally extending slots, the walls of which act as guides, means for adjustably securing one end of a belt to the front portion, springs mounted in said tubes, a cross bar having its ends guided on the walls of the slots and connecting with the springs in the tubes the cross bar being spaced between its ends from the plane of the rear face of the front portion, so that a belt end secured by the adjustable securing means may lie 80 between the cross bar and the front portion. 85

7. A buckle, comprising a frame having longitudinal cylindrical chambers in the sides extending throughout the length thereof, longitudinal slots narrower than said chambers in the walls thereof opening into said chambers, a plate mounted in said frame between said chambers and having its side edges flanged and extending through said longitudinal slots into said chambers, coiled compression springs enclosed in said chambers and engaging said flanges, and a strap connected at one end to the frame and at its other end to said flanged plate one of said connections being adjustable. 90 95

8. A buckle, comprising a metal sheet having the edges curled inwardly to form longitudinal beads, the edge of said beads being spaced from the back of the plate and forming longitudinal slots, said plate having turned up end flanges closing the recesses, a slideable member arranged between said beads and having edge flanges extending through the slots into said beads, said slideable member having upturned lug ends, compression springs arranged within said beads engaging the flange at one end thereof and engaging the lugs on said movable member and adapted to hold the movable member toward one end of the buckle frame, a strap connected at one end to the frame and at its other to said movable member one of said connections being adjustable. 100 110 115

120 125 130

9. A belt buckle comprising a frame, a cross bar bridging the frame, a belt securing tongue pivoted to the cross bar, guides extending longitudinally of the frame and on opposite sides of the cross bar, a belt anchoring bar, and lateral extensions on the opposite ends of the belt anchoring bar mov-

able in said guides, the belt anchoring bar connecting the extensions at a point between the two ends of the frame when the belt anchoring bar is in normal position.

5 10. A belt buckle comprising a frame formed from a single piece of sheet metal and having two end pieces, two side pieces, a cross bar connecting the side pieces in spaced relation to both end pieces, the side

pieces having extensions turned over but 10 spaced therefrom at the free edges to provide tubes and slots on the inner sides of the tubes, springs mounted in the tubes, a belt anchoring member having connection with the springs through said slots and means supported by the cross bar for adjustably securing the opposite end of the belt. 15
